UNITED STATES PATENT OFFICE.

W. M. RICE, OF BOSTON, MASSACHUSETTS.

IMPROVED HEEL-IRONS.

Specification forming part of Letters Patent No. **58,675**, dated October 9, 1866.

To all whom it may concern:

Be it known that I, WALTER M. RICE, of Boston, Suffolk county, State of Massachusetts, have invented a new and useful and Improved Heel-Iron for Boots and Shoes; and I do hereby declare the following description and accompanying drawings are sufficient to enable any person skilled in the art or science to which it most nearly appertains to make and use my said invention or improvements without further invention or experiment.

The nature of my invention and improvements consists in making heel-irons for boots and shoes far thicker, or twice as thick, on the rear and out sides of the heels as they are on the front and in sides of the heels; also, in making the interior of the heel-irons beveling in the interior, so as to fasten them onto the heels of boots or shoes by nailing or pegging the leather fitted to the interior of the heel-iron to the heel of the boot or shoe.

In the accompanying drawings, Figure 1 is a perspective view of my improved heel-iron. Fig. 2 is a plan of a heel with the iron fastened to it. Fig. 3 is a section of Fig. 2 on the line *xx*.

In these drawings, A is the front of the heel-iron; B, the rear; C, the outside, and D the inside—that is, D is the side of the iron which is worn on that side of the heel next to the other foot, and C the opposite side from the other foot, which I call the "outside."

In the drawings, the parts B and C are represented much thicker than, or nearly twice as thick as, the parts A and D.

I make my improved heel-irons in pairs, and apply them to the heels of boots and shoes with the thick sides to the outsides of the

heels and the thin sides to the insides of the heels, as most people wear off the rears and outsides of the heels of their boots and shoes much faster than they do the fronts and insides; and making the heel-irons thicker where there is the most wear and thinner where there is the least wear is intended to make them wear more uniformly or evenly, and prevent the boot or shoe from crowding over in the rear or on one side, and make the boots and shoes wear longer than when the heel wears off in the rear or one side.

I make the upper-side of my heel-irons twice or several times as thick as the under side or edge, as shown in Fig. 3, by beveling the interior of the iron, so that a piece of leather may be fitted to the interior of the iron and pegged or nailed to the heel, as shown in Figs. 2 and 3, to hold the iron on the heel of the boot or shoe, thereby saving the necessity of making holes in the irons to fasten them to the leather heels, as heretofore practiced.

My improved heel-irons may be made very cheap of cast or malleable iron, which induces me to hope they will go into general use.

I claim—

As a new article of manufacture, the above-described heel-irons—to wit, heel-irons made thickest on that part or side which usually wears out fastest and beveled on the inside, as described, so as to be held onto the heel by the leather nailed or pegged in the inside of said irons.

WALTER M. RICE.
